UNITED STATES PATENT OFFICE.

THOMAS LINDSAY MOORE, OF SAN ANTONIO, TEXAS.

RAILWAY SIGNALING-LANTERN.

No. 823,615.

Specification of Letters Patent.

Patented June 19, 1906.

Application filed December 30, 1905, Serial No. 293,950.

To all whom it may concern:

Be it known that I, THOMAS LINDSAY MOORE, a citizen of the United States, residing at San Antonio, in the county of Bexar, 5 and State of Texas, have invented a new and useful Railway Signaling-Lantern, of which the following is a specification.

This invention relates to lanterns, and in particular to railway signaling-lanterns as 10 employed by brakemen and switchmen for signaling to the engineers of trains and specially for directing the movements of switching-engines.

The object of the present invention is to 15 equip such lanterns with a novel arrangement of handle whereby the lantern may be more conveniently handled to more accurately produce signals, and thereby avoid confusion which frequently results from the 20 conventional form of lantern having the usual swinging handle.

With these and other objects in view, which 25 will appear as the nature of the invention is better understood, the invention consists in certain novel features of construction, as hereinafter fully described and claimed.

In the accompanying drawings, forming a 30 part of this specification, and in which corresponding parts are denoted by like designating characters, is illustrated the preferred form of embodiment of the invention capable of carrying the same into practical operation, it being understood that various changes in the form, proportion, and minor details of 35 construction may be resorted to without departing from the principle or sacrificing any of the advantages of this invention within the scope of the appended claims.

In the drawings, Figure 1 is a side elevation of a lantern with the improvement applied. Fig. 2 is a detail view of a portion of the guard-frame and a portion of one of the handle-standards, illustrating the construction. Fig. 3 is an enlarged sectional detail 45 of a portion of the improved handle.

One of the most important duties of railway switchmen is to transmit signals at night by swinging a lantern held in the hand, and many of these signals are so nearly alike 50 that a slight variation often causes serious accidents. In using the lantern as ordinarily constructed, with the bail of relatively thin wire and swinging upon the lantern, it is difficult to grip the bail with sufficient force

to prevent slipping, and thus interfering with 55 the proper transmission of the signal.

The principal object of the present invention is to construct a lantern handle or bail which may be firmly grasped by the hand, and thus enable the operator to control the 60 motions and accurately transmit the signals and reduce to the minimum the chances for error.

The invention consists, primarily, in a handle substantially in U shape, with the central 65 or grip portion enlarged and preferably formed of wood and rigidly connected to the frame of the lantern at its ends.

The improved device may be applied to any of the various makes of lanterns employed by switchmen, but for the purpose of illustration is shown applied to a conventional structure of this class, the base being represented at 10, the oil-receptacle at 11, the burner at 12, the guard-frame formed of 75 vertical members 13 and horizontal member 14, the top or head 15, and the globe 16.

Connected at the ends, respectively, to the base 10 and head 15 are spaced standards 17 80 18 and also connected to the horizontal member 14 of the guard-frame by coiling around the same, as at 19 20, and formed with laterally-extending guide-loops 21 22. The handle member is constructed of two rods 23 24, extending through the guides 21 22 and connected to the horizontal guard member 14 by coiling around the same, as represented at 25 26. The upper ends of the rods 23 24 are enlarged into tapering sockets 27 28, and into these sockets the tapered ends of the U- 90 shaped grip member 29 are inserted and secured by pins 30 31 or by other suitable means. The member 29 is preferably of wood bent into the required shape and considerably larger in transverse section than 95 the rods 23 24, so as to enable the operator to firmly grip the same when handling the lantern. The lantern and bail are thus rigidly united, and the bail is large enough to be firmly grasped, thus enabling the operator to 100 effectually control the motions required in transmitting signals therewith and reducing to a minimum the chances for error.

Having thus described the invention, what is claimed is—

1. The combination with a lantern including a guard-frame, of spaced standards connected to said frame and provided with later-

ally-extending guides, rods connected at the lower ends to said frame and extending through said guides and provided with sockets at the upper ends, and a **U**-shaped grip member connected at its ends in said sockets.

2. A lantern having a wire cage to protect the chimney thereof, diametrically opposite wires of the cage being provided with transversely-disposed loops, rods carried by the lower portion of the cage and rising through the respective loops, and a handle connecting the upper ends of the rods and arched over the top of the lantern.

3. A lantern having a cage to protect the

chimney thereof, rods rising from the cage at 15 diametrically opposite sides thereof and provided at their upper ends with sockets, and an arched handle of heat-non-conducting material spanning the top of the lantern and having its ends seated within the sockets.

20 In testimony that I claim the foregoing as my own I have hereto affixed my signature in the presence of two witnesses.

THOMAS LINDSAY MOORE.
